UNITED STATES PATENT OFFICE

MURVALE I. HIGBIE, OF NEW YORK, N. Y.

PAPER CUTTER

Application filed September 5, 1928. Serial No. 303,994.

This invention relates to a paper cutter, and has for an object to provide an improved construction which is adapted to be worn on a finger and readily manipulated 5 to cut paper supported on a pad or other support.

Another object of the invention is to provide a paper cutter using either a thick or wafer blade with means for quickly applying or removing the blade.

A further object, more specifically, is to provide a paper cutter wherein a portion is formed to resiliently grip a finger and an extension is provided for receiving and 15 clamping a blade in place so that part of the edge and one corner will be in functioning position at all times.

In the accompanying drawing—

Figure 1 is a side view of a paper cutter 20 embodying the invention, the same being shown in position on a hand indicated by dotted lines.

Figure 2 is a perspective view of the cutter shown in Figure 1 with parts thereof 25 broken away for clearness of illustration, the view being taken from the opposite side.

Figure 3 is a detail perspective view of a clamping plate embodying certain features of the invention.

Figure 4 is a side view of the blade used 30 in Figure 1.

Fig. 5 is a detail fragmentary sectional view through Fig. 1, on line 5—5.

Fig. 6 is a detail fragmentary perspective view of a portion of the device.

Referring to the accompanying drawing by numerals, 1 indicates a blade having a cutting edge 2 arranged so that the corner 3 will act as the principal part of the cutting structure 40 when the device is in use as shown in Figure 1. The blade 1 has been shown as a wafer blade, but if desired, a heavier blade could be used and one with one or two edges used, though only one edge would operate at a time. Co- 45 acting with the blade 1 is a clamp 4 for clamping the blade onto the supporting base 5 which is preferably formed integral with a carrier ring or clamp 6. The carrier 6 is preferably a substantially tubular structure of 50 metal, provided with overlapping extensions

7, 8 and 9, extension 9 projecting into the notch 10. Preferably these extensions are slightly bent or flared at the ends so as not to pinch against the finger when the device is in use, and also to permit the device to be readily spread or brought together to properly fit the finger.

The carrier 6 is preferably made from sheet metal, as for instance, steel or aluminum, and is more or less resilient, though it may be bent permanently to fit the finger and then a slight resilient action will maintain a proper clamping action. The tubular member or carrier 6 merges into the base 5 and is in fact, an integral part thereof.

The base 5 is substantially triangular in shape 65 and is formed with turned over ears 11 and 12, said ears co-acting with a turned over ear 13 pressed from carrier 6 as shown in Figure 1. These ears form a passage-way for clamp 4 and ear 11 forms a back rest for blade 1 70 when in use. The clamp 4 is provided with a flange 14 and a turned over hook portion 15, said hook portion preferably fitting snugly over the rear face of base 5 as shown in Figure 2, while the front part of the clamping plate 4 75 presses the blade 1 against base 5. The ear 12, as shown in Figure 1, faces to the left and, therefore, forms an abutment against which the end 16 of blade 1 rests when in operative position as shown in Figure 1, and also 80 against which the shoulder 17 of plate 4 rests.

A short turned up ear 12' closes the ear 12 on the lower edge when looking at the same as illustrated in Figure 1, but provides a support for the rear part of the cutting edge 2, as illustrated in Figure 5. The ears 11 and 13 on one side and the ear 12 on the opposite side form a pocket closed on two sides and open on two sides, said pocket receiving part of the clamping plate 4 and part of the blade 1. The hook 15 acts on the end 18 for holding the blade in place and against ear 12. Preferably the ears 11, 12 and 13 are resilient and are spaced from the base 5 sufficiently to permit 90 the plate 4 to slide therebeneath but be resiliently clamped. The flange 14 acts as a rest for the thumb when the device is in use, while the forefinger is folded and rests on the article to be cut. In this way, the knife 1 may be 100

properly guided during the cutting operation.

Whenever the knife 1 becomes dull, the clamp or clamping plate 4 may be removed by pushing the same towards the left in Figure 1. The blade 1 will then drop out and a new blade may be inserted, after which the clamping plate 4 is re-applied and pressed as near to the position shown in Figure 1 as possible. When the device is on the forefinger, but is not in cutting position as shown in Figure 1, the edge 2 is facing away from the person using the device, particularly if the forefinger is in a substantially horizontal position. In this way, the cutting edge is always in a position which will permit a quick shifting of the parts so that the edge may be used for cutting, while at all times the edge is out of the way of the fingers of either hand or any part of the body.

20 What I claim is:

1. A paper cutter, comprising a securing member adapted to clamp a finger of a hand when the device is in use, a base extending from said securing member, said base being flat, a plurality of clamping ears overlapping said base, one of said ears being positioned to act as an abutment, a blade fitted flatwise against said base and positioned with one end engaging said abutment, and a sliding flat clamping plate adapted to fit flatwise against said blade and beneath said ears for clamping said blade on said base, said clamping plate being formed with an extension projecting at right angles to the remaining part of the plate for acting as a guide and thumb rest.
2. A paper cutter, comprising a holding member, a base extending from said holding member, said base presenting a flat surface, a plurality of overlapping ears overlapping said flat surface, a blade fitted against said surface and abutting against the base of one of said ears, a flat clamping plate fitting beneath said ears for clamping said blade in place, said plate being formed with a hook extending over one end of the blade and over one end of said base, said clamping plate being also formed with a shoulder fitting against the base of one of said ears.
3. A paper cutter, comprising a supporting member, a base extending from the supporting member, a blade fitted against said base, a clamping plate for clamping said blade in position, said clamping plate having a projecting flange acting as a thumb rest, and means extending from said base fitting over said clamping plate for holding the clamping plate in position.
4. A paper cutter, comprising a tubular holding member, a flat base merging into said holding member, said base being provided with integral extensions bent to produce overlying ears, a blade fitted against said base and positioned with one edge under

two of said ears and part of the opposite edge under one of said ears, a clamping plate fitted against said blade and positioned with its edges under said ears, said plate being formed with a hook hooking over one end of said blade and also one end of said base, and with a flange adjacent the opposite end acting as a thumb rest and guide.

Signed at New York in the county of New York and State of New York this 1st day of September, A. D. 1928.

MURVALE I. HIGBIE.
